WINDING APPARATUS

Peter J. Christman, Green Bay, Wis.

Application April 1, 1940, Serial No. 327,124

8 Claims. (Cl. 242—56)

This invention relates to winding apparatus which is particularly adapted for forming toilet rolls, towel rolls, etc.

Heretofore in the forming of paper rolls, it has been necessary to stop the winding operation after one roll or set of rolls has been completed. Further, in the starting of new rolls, an uncertain winding operation has resulted from methods employed, such as, for example, the mandrel upon which the new roll is to be formed.

An object of the present invention is to provide means for continuously winding rolls, the winding apparatus being kept continuously in operation. A further object is to provide a non-stop winding machine in which a paper or other web is continuously drawn upon cores, the cores being removed and new cores inserted without causing a pause in the winding operation. A further object is to provide greater certainty in operation and a better product by avoiding wetting of the cores and paper and providing a more positive means for holding the paper upon the core. Other specific objects and advantages will appear as the specification proceeds.

The invention is illustrated, in a preferred embodiment, by the accompanying drawing, in which:

Figure 1 is a schematic showing of the apparatus employed, the apparatus being shown in side elevation and partly in section; Fig. 2, a view similar to Fig. 1 but showing only the forward portion of the apparatus with the web cutting device in operative position; Fig. 3, an enlarged, broken plan view of a mandrel over which a core is partially advanced; Fig. 4, an enlarged, transverse sectional view, the section being taken as indicated at line 4 of Fig. 3; Fig. 5, an enlarged plan view of a portion of the cutting knife employed; and Fig. 6 is a side elevational view of the cutting disks in engagement with a core.

In view of the fact that the greater portion of the apparatus shown in the drawing is of old and well-known construction, a detailed description thereof will not be necessary. The web of paper or other material is indicated by the numeral 10, and it is drawn over a perforating bed roll 11, being held against the roll by the pull rolls 12 and 13. Above the perforating bed roll is rotatably supported the well-known adjustable perforating head 14. From the perforating structures just described, the web 10 passes over the slitter board 15 and beneath the slitter discs 16. The slitter discs 16 are driven by a belt 17 secured to a drive 18.

A cutting knife 19 is supported upon an arm 20

so as to be dropped at the desired time into contact with the web 10 and to sever it, the severing position of the knife being shown in Fig. 2. The blade of knife 19 is provided with serrated edges 21, as shown more clearly in Fig. 5.

After the web 10 passes beyond the slitter block 15, it passes under an idler roll 22.

The winding apparatus consists of a number of rotatable mandrels carried upon a rotatable support 23. In the illustration given, there are three mandrels 24 and each is supported upon a somewhat circular frame extension 25 projecting from the main support 23. The support 23 is rotatably mounted upon shaft 26. Such apparatus is of well-known construction and need not be described in detail. In such well-known construction, drive apparatus (not shown) engages the mandrel when it is in the position indicated by the letter A, thus causing the paper web 10 to form a roll upon the core 27 carried by the mandrel. When the support 23 is swung so that the rotating mandrel just described is moved to the position indicated by the letter B, the mandrel is no longer rotated and the core 27 carrying the completed roll can be withdrawn, since in this operation the knife 19 severs the web just ahead of position B, as shown more clearly in Fig. 2. After the roll or set of rolls on the mandrel in position B is withdrawn, new cores 27 may be inserted upon the mandrel 24. The mandrel with the core thereon may then be moved to the slot cutting position indicated by the numeral C. Here slots are formed in the core made of cardboard or other material, the slots being indicated by the numeral 28.

Each of the mandrels 24 is provided with a hollow, longitudinal opening and with lateral openings 29 extending from the central passage. The lateral passages 29 open within grooves 30 formed at spaced intervals along the mandrel 24. When the core 27 is in the proper position, the slots 28 are aligned with the grooves 30 so that suction is applied through the central passage in the mandrel and from thence through the openings 29 and the slots 28. When the mandrel 24 is swung into position A, the opening in the center of the mandrel communicates with a suction device (not shown), so that direct suction is applied through passages 29 and slots 28.

If desired, the core 27 may be already perforated or slotted before it is inserted upon the mandrel 24. In the particular illustration given, however, I provide for slotting the core after it has been placed upon the mandrel. The core can be more readily inserted upon the mandrel

in tight relation therewith prior to the forming of slots and there is the further advantage that by the cutting operation brought about in position C, an accurate alignment of the slots with the grooves 30 is insured. In position C, the shaft 31 is rotated so as to bring the spaced cutter discs 32 into cutting relation with the core 21, thus forming the short slot 28 in the core.

Operation

In the operation of the apparatus, the web 10 passes over the perforating bed roll 11, being held tightly thereagainst by the pull rolls 12 and 13, and the desired perforation is formed therein by means of the rotation of the perforating head 14. The roll is slit, in the usual manner, over the slitter board 15 by means of the slitter discs 16. It passes under the idler roll 22 and is wound upon the core 21 frictionally engaging the mandrel 24 in position A. After the roll has been substantially finished, as illustrated in Fig. 2, the supporting member 23 is rotated so as to bring the winding mandrel to position B. Here the mandrel ceases to rotate. Meanwhile, the mandrel which was formerly in position C is swung to position A, where it is engaged by the drive apparatus and set in rapid rotation. The cutting knife 19 descends at this moment and cuts the web 10 between positions A and B. The completed roll on the core in position B may then be removed from the non-rotating mandrel and a new core inserted upon the mandrel.

Upon the severing of the web, the portion of the web near the mandrel in position A, in which suction is now effective, curls tightly around the mandrel and is held firmly thereon by suction. The rotation of the mandrel proceeds rapidly so as to form the next roll.

While the above operations are being carried on in positions A and B, the core which was inserted upon the mandrel formerly in position B and now in position C, is provided with a plurality of spaced slots 28 aligned with the grooves 30. In this manner, the core is provided with suction openings communicating with the suction openings of the mandrel and is thus ready for the suction operation which starts when the core is moved to position A.

There is thus provided a cycle of operations in which the winding of the paper web, the removal of the finished roll and the slotting of the core are accomplished without interruption of the winding operation. The knife is operative for severing the web at the precise moment when the finished roll is moved out of winding position and when a new core is brought into winding position, the severed portion of the web adjacent the winding core being just about sufficient in length to engage the winding core and form a gripping contact therewith so that the forward movement of the web continues without interruption.

If the cores are perforated prior to their insertion upon the mandrels, it will be understood that step C may be omitted. As already pointed out, however, step C is particularly useful in that it insures accurate alignment of the slots with the cores irrespective of the position of the core upon the mandrel, while at the same time it enables an unslotted core to be placed upon the mandrel in position B.

While in the foregoing description, I have set forth certain details and certain steps as desirable, it will be understood that such steps

and details may be varied widely without departing from the spirit of my invention.

I claim:

1. In apparatus of the character set forth, a frame, a plurality of spaced mandrels movably supported thereby, means for rotating a mandrel when moved into web-winding position, means for moving a first mandrel beyond winding position and simultaneously moving a second mandrel into winding position, the web carried by said first mandrel being brought adjacent said second mandrel, means for severing said web between said first and second mandrels, said mandrels being provided with a plurality of suction openings adapted to cause the free end of the severed web to adhere to the mandrel automatically when under the influence of suction, and means for creating suction in the openings of said second mandrel when in winding position.
2. In apparatus of the character set forth, a frame, a plurality of spaced mandrels movably supported thereby, core members removably carried by said mandrels, means for rotating a core-equipped mandrel when moved into web-winding position, means for moving a first mandrel beyond winding position to permit the removal of the core thereon and for simultaneously moving a second mandrel into winding position, the web carried by said first mandrel being brought adjacent the core of said second mandrel, said core being equipped with openings therein, means for severing said web between said first and second mandrels, and suction means carried by said second core-equipped mandrel in winding position for creating suction in the openings in the core carried thereby to cause the leading free end of said severed web to adhere automatically to the core of said second mandrel.
3. In apparatus of the character set forth, a frame, a plurality of spaced core-equipped mandrels movably supported thereby, means for rotating a mandrel and the core carried thereby when moved into web-winding position, means for moving a first mandrel beyond winding position and simultaneously moving a second mandrel into winding position, the web carried by said first core-equipped mandrel being brought adjacent the core of said second mandrel, means for severing said web between said first and second mandrels and pressing the leading severed end portion towards the second mandrel, said mandrels and the cores carried thereby being provided with a plurality of suction openings adapted to cause the free end of the severed web to adhere to the mandrel automatically when under the influence of suction, and means for creating suction in the passages of said second mandrel when in winding position.
4. In apparatus of the character set forth, a frame, a plurality of spaced mandrels movably supported thereby, said mandrels being provided with suction openings communicating with the exterior of said mandrels, cores extending over said mandrels and covering said openings, means for rotating a mandrel when moved into web-winding position, means for moving a first mandrel beyond winding position and simultaneously moving a second mandrel into winding position, the web carried by said first mandrel being brought adjacent said second mandrel, the core of said first mandrel being removable in said non-winding position and being adapted to receive a second core, means for cutting slots in said second core while on the mandrel to establish com-

munication between said slots and the suction passages in said mandrel, means for severing said web between said first and second mandrels, and means for creating suction in the passages of said second mandrel when the same is moved into winding position, said suction causing the leading free end of said severed web to adhere automatically to said second mandrel.

5. In winding apparatus, a frame, a movable support member mounted thereon, a plurality of spaced mandrels carried by said support and having suction openings therein, each of said mandrels being movable by said support into a web-winding position and a non-winding position, means for rotating a mandrel when in winding position and means for creating suction in the suction openings of the mandrel when the same is in winding position, removable cores provided with openings communicating with the suction openings in said mandrels, and cutting means operative when the winding mandrel is moved to a non-winding position and another mandrel is moved to a winding position for cutting the web between said last-mentioned mandrels and directing the leading severed end portion into the pneumatic grip of the mandrel in winding position.

6. In winding apparatus, a frame, a movable support member mounted thereon, a plurality of spaced mandrels carried by said support and having suction openings therein, each of said mandrels being movable by said support into a web-winding position and a non-winding position, means for rotating a mandrel when in winding position, means for creating suction in the suction openings of a mandrel when the same is in winding position, removable friction cores extending over the suction openings in said mandrels, means for forming slots in the core on a mandrel in register with the suction openings in the mandrel, and web cutting means operative when the winding mandrel is moved to a non-winding position and another mandrel is moved to winding position for cutting the web between said last-mentioned mandrels.

7. In continuous winding apparatus, a frame, a rotatable support member mounted thereon, a plurality of spaced mandrels carried by said support and having grooves formed in their surfaces, said mandrels having a central suction passage and radial passages communicating with said grooves, each of said mandrels being movable by rotation of said support into a web-winding position and a non-winding position, means for 10 rotating a mandrel when in winding position, means for creating suction in the central suction passage of the mandrel when it is in winding position, removable friction cores extending over said mandrels and covering said grooves, means engageable with said grooves for forming slots in said cores aligned with said grooves, and cutting means operative when the winding mandrel is moved to a non-winding position and another mandrel is moved to a winding position for cutting the web between said last-mentioned mandrels.

8. In winding apparatus, a frame, a rotatable support member mounted thereon, three spaced mandrels carried by said support and having spaced grooves extending about their periphery, said mandrels also having a central suction passage and radial passages establishing communication between said central passage and said grooves, each of said mandrels being movable by rotation of said support into web-winding position and two non-winding positions, the mandrels in non-winding positions being adapted to receive new cores, and cutting means supported adjacent one of said non-winding positions for 25 engaging the core and cutting therethrough into the grooves to form aligned slots with said grooves, and cutting means operative when the winding mandrel is moved to a non-winding position and another mandrel is moved to winding position for cutting the web between said last-mentioned mandrels.

PETER J. CHRISTMAN.
